UNITED STATES PATENT OFFICE.

PERCIVAL F. BRINE, OF BOSTON, MASSACHUSETTS, ASSIGNOR TO OIL WELLS RENEWAL COMPANY, OF CHICAGO, ILLINOIS, A CORPORATION OF DELAWARE.

ELECTRICAL HEATER FOR OIL WELLS.

Application filed March 22, 1921. Serial No. 454,582.

To all whom it may concern:

Be it known that I, PERCIVAL F. BRINE, a citizen of the United States, residing at Boston, in the county of Suffolk, and State of Massachusetts, have invented an Improvement in Electrical Heaters for Oil Wells, of which the following description, in connection with the accompanying drawings, is a specification, like characters on the drawings representing like parts.

The invention to be hereinafter described relates to electric heaters for oil wells.

Paraffine and other products accumulate in oil wells, and materially interfere with the free flow of the oil from the terrain into the wells, with consequent reduction of the output of the well.

One of the purposes of the present invention, therefore, is to provide a simple, efficient, commercially practicable heater which may be lowered into the oil well, and raise the temperature therein so as to fuse or melt the paraffine and other heavy products, so that they will not obstruct the free flow of oil into the well from the surrounding oil bearing terrain.

Another purpose of the invention is to provide a heater of a length which may be substantially equal to the depth of the sand stratum through which the oil flows into the well, the construction being such that paraffine or other obstructing matters may be melted and removed throughout the depth of the portion of the oil well which extends through the sand stratum. In carrying this feature of the invention into practical effect, simple, efficient means is provided for providing a strong, durable construction for the purpose.

Another object of the invention is to provide simple and efficient means for conducting the electric current to the heater, and for raising, lowering and suspending the heater.

With the aforesaid and other purposes in view, the character of the invention will be best understood by reference to the following description of one good form thereof shown in the accompanying drawings, wherein:

Fig. 1 is a side elevation of an electric heater embodying the invention, certain parts being shown in section;

Fig. 2 on an enlarged scale is a vertical longitudinal section through the heater;

Fig. 3 is a horizontal section taken on line 3—3 of Fig. 2;

Fig. 4 is a horizontal section taken on line 4—4 of Fig. 2;

Fig. 5 is an end view of the lower end 60 of the heater;

Fig. 6 on an enlarged scale is a vertical section through one of the heater units;

Fig. 7 on an enlarged scale is a horizontal section taken on line 7—7 of Fig. 6; 65

Fig. 8 is a horizontal section taken on line 8—8 of Fig. 2;

Fig. 9 is a horizontal section taken on line 9—9 of Fig. 2; and

Fig. 10 is a section through end portions 70 of tandem heating units.

Referring to the drawings, the heater shown therein as one good form of the invention, comprises preferably a plurality of heater units 1, and since these units are 75 similar in construction, a description of one will suffice for all.

Each of these units comprises a tube or container 3 (Figs. 2 and 6) of wrought iron or other suitable material containing an electric resistance wire or coil 5 of nichrome metal or other suitable composition. The outer diameter of the convolutions of this coil is substantially less than the internal diameter of the tube 3. The upper end of 80 the coil is connected to a binding post 7 secured in a plug 9 insulated from the tube 3 by a sleeve 11 of mica or other suitable insulation material.

The lower end of the coil is connected to 90 a stud 13 having a portion 15 threaded into a plug 17 entered into the tube 3 and separated therefrom by a sleeve 19 of mica or other suitable insulation material. The stud 13 has a portion 21 threaded into a plug 17 95 of a similar heating unit, as more fully hereinafter described.

Suitable substance or material may be provided to transmit the heat of the electric resistance coil 5 to the tube 3. The material, 100 in the present instance, is in the form of finely ground or pulverulent mica 23 which is introduced into the tube so as to surround the coil and fill the space between the coil and the tube.

Heretofore, so far as I am aware, in oil well heaters the space between the electrical resistance wire or tube has been occupied by air or other gas, so that the heat must be transmitted by radiation from the wire or 110

coil to the tube containing it. In the present construction, on the other hand, the heat is directly conducted by the powdered mica from the coil to the tube, with materially 5 more efficient heating effect.

In some instances a unit such as described may be sufficiently long to serve the purposes required. In other instances it may be desirable to provide a heater of greater length.

- 10 To accomplish this, a plurality of such heater units may be provided in end-to-end or tandem relation. For purposes of illustration, two such units are shown in end-to-end relation, and are connected by the threaded stud 15 13 referred to, which may have asbestos insulation 14.

To strengthen the construction and securely hold the units in proper alignment, they may be introduced with a close fit into a tube

- 20 25 of copper or other suitable material, having a length substantially corresponding to the number of heater units employed in end-to-end relation.

There is no air space between the unit 25 tubes 3 and the outer tube 25, and as a consequence, the heat is directly conducted from the coil through the powdered mica to the tubes 3, and thence through the outer tube 25 to the oil surrounding the latter.

- 30 The number of heating units may be varied as required, but in the present instance of the invention, six such units are arranged in a group and conveniently disposed in a circle.

- 35 The upper ends of the outer tubes of the units may be entered into holes in an upper head 27, and may be brazed or otherwise secured in said holes. The lower ends of the outer tubes of the units may be entered into 40 holes in a lower head 29, and may be brazed or otherwise secured thereto.

- To strengthen the tubes and hold the same in proper spaced relation, members or disks 31 may be provided at suitable intervals intermediate the upper and lower heads, and may have holes extending therethrough, through which the outer tubes are inserted and brazed or otherwise secured thereto.

- 45 The lower head 29 may have a cap 33 desirably of conical form and provided with a flange 35 connected by screws 37 with the head 29, a gasket 39 of asbestos or other suitable material being interposed between the body and cap to prevent entrance of oil into the head. A filling 41 of asbestos or other suitable material may be provided for the lower head 29 further to prevent leakage of oil into the head.

- 50 The binding posts 7 for the lower ends of the units may project into the lower head, and pairs of said binding posts may be connected by bridge plates 43 (Fig. 9) apertured to receive said binding posts, and held by adjusting nuts 45.

- 60 65 The means for supporting the heater and

supplying electric current to the units, in the present instance of the invention, is in the form of a heavy conducting cable 49 (Figs. 1, 2 and 4) comprising a strong fabric 51 enclosed by heavy spirally wound wire strands 70 53. The lower end portions of these wires may be unwound and divided into groups of wires 55 which may be looped through eyes in ears 57 projecting from a flange 59 of a collar 61 secured by screws 63 to the upper 75 head 27, a gasket 65 of asbestos or other suitable material being interposed between the sleeve flange and the upper head to prevent leakage between them.

The internal diameter of the sleeve 61 may be substantially the same as the external diameter of the cable fabric 51, which may have a lower end portion projecting down through said sleeve. To prevent leakage, the sleeve 61 may have a recess therein receiving a packing 67 of asbestos or other suitable material held by a gland 69 which may be adjusted downward and secured by a flange collar 71 threaded to the sleeve 61.

In the present instance, the electrical conducting cable contains three conductors 73 enclosed in rubber tubes 75 encased by fabric tubes 77 which are encased in turn by the tubular fabric 51 referred to.

The pairs of units which are not connected by the lower bridge plates 43 may be connected by upper bridge plates 78. The conductors 73 may project down into the upper head and have contact arms 79 apertured and secured by nuts 81 and 83 to alternate posts 100 of the upper binding posts 7. The construction is such that the units are connected in series and receive polyphase alternating currents, although direct current could be used if desired.

105 The space in the upper head 27 surrounding the electric conductors may be filled with asbestos 85 or other suitable material. The construction is such that the cable 49 serves the dual function of containing the electric conductors which supply the current to the heating unit, and of supporting the heater. As a result, the heater may be raised or lowered and suspended by a strong cable, and the conductors are contained within the cable so as to be protected thereby. The necessity of separate cables to supply the current to the heater and to support the heater is eliminated.

110 115 120 In operation, the heater may be lowered into the oil well, and electric current may be furnished from any suitable source of supply to the heater. When the current is turned on, it will pass through the conductors to the heating units, and as it passes through the electric resistance coils of the units, they will become quickly heated, and this heat will be directly transmitted or conducted by the pulverulent mica to the 130

tubes 3 and the outer tubes 25, and since the latter are in direct contact with the oil in the well, the latter will be directly heated, and its temperature will be quickly raised to the proper point for fusing or melting the paraffine or other products in the bottom of the well and along the walls thereof which interfere with normal flow or entrance of oil from the sand stratum of the terrain into the well. As a consequence, the output and capacity of the well will be greatly increased.

The heater described is strong and simple in construction, and efficient in operation.

15 It will be understood that the invention is not limited to the specific embodiment shown, and that various deviations may be made therefrom without departing from the spirit and scope of the appended claims.

20 What is claimed is:—

1. An electric heater for oil wells, comprising a pair of hollow liquid tight heads, tubes connecting said heads, electrical resistance coils mounted within the tubes in spaced relation to the walls thereof, a substance filling the space between the coils and the tubes for conducting heat from the coils to the tubes, tube spacing means located intermediate said heads to hold the tubes in spaced relation, and conductors for supplying current to said coils.

25 2. An electric heater for oil wells, comprising a pair of hollow liquid tight heads, tubes connecting said heads, electrical resistance coils mounted within the tubes in spaced relation to the walls thereof, conductors within the heads for said coils, powered insulating material packed within the heads to form a conductor for heat and 30 to further exclude liquid from the conductors, a cable extending into one of said heads, and a stuffing box for preventing liquid from entering the head about the cable.

35 3. An electric heater for oil wells, comprising a pair of heads, tubes connecting said heads, electrical resistance coils mounted within the tubes in spaced relation to the walls thereof, a pulverulent substance 50 filling the space between the coils and the tubes for conducting heat from the coils to the tubes, tube spacing means located intermediate said heads to hold the tubes in spaced relation and comprising a disk having spaced apertures through which the tubes extend, and conductors for supplying current to said coils.

40 4. An electric heater for oil wells, comprising a hollow liquid tight head, tubes connected to said head and extending therefrom, electrical heating coils mounted within the tubes in spaced relation to the walls thereof, a supporting cable secured to the head and having conductor wires within 45 the cable that extend into the head, and

packing means for preventing moisture from entering the head about the conductor wires.

5. An electric heater for oil wells, comprising a pair of liquid tight heads, tubes connecting said heads, electrical heating coils mounted within the tubes in spaced relation to the walls thereof, conductors within said heads for the coils, a pulverulent substance filling each head further to prevent moisture from reaching the conductors, a cable for supporting the heater and surrounding conductor wires that extend into one of said heads and supply current to the coils.

6. An electric heater for oil wells, comprising upper and lower heads, heating units connected to said heads, each comprising a wrought iron tube, a copper tube receiving and closely fitting the wrought iron tube 55 and having ends secured in said heads, an electric resistance coil mounted in said wrought iron tube and spaced and insulated therefrom, and pulverulent mica filling the space in the iron tube surrounding the coil 60 for directly conducting the heat from the coil to the iron tube.

7. An electrical heater for oil wells, comprising a pair of heads, tubes connecting said heads, electrical resistance coils mounted in and spaced from said tubes, a substance filling the space between the coils and the tubes for conducting heat from the coils to the tubes, and a cable having electrical 75 conducting wires projecting into the upper 100 head and supplying current to said coils, said cable having wires secured to said head for supporting the heater.

8. An electrical heater for oil wells, comprising upper and lower heads, tubes connecting said heads, electrical resistance members in said tubes and spaced and insulated therefrom, pulverulent mica filling the space between the electrical resistance members and tubes for conducting the heat 110 directly from the former to the latter, a cable having wires secured to the upper head, and conducting wires projecting into said head to supply current to said electrical resistance members, and means to prevent leakage of 115 oil past said cable into the head.

9. An electrical heater for oil wells, comprising upper and lower heads, containers connecting said heads, electrical resistance members in said containers and spaced and insulated therefrom, a pulverulent substance filling the space in the containers surrounding the electrical resistance members, a heavy cable provided with a wire sheath thereon having end portions secured to the upper head to support the heater, and conducting wires in said cable projecting into said head for supplying electrical current to the resistance members.

10. An electrical heater for oil wells, com- 120

- prising a head, a plurality of heating units secured to and depending from said head, each of said units comprising a tube secured to said head, an electrical resistance coil in said tube and spaced and insulated therefrom, powdered mica filling the space between the coil and the tube to conduct heat from the former to the latter, a cable connected to said head for supporting the heater and having conductors for supplying current to the electric resistance coils. 35
11. An electrical heater for oil wells, comprising a head having a collar secured thereto provided with apertured ears, heating units secured to and depending from the head, each comprising a tube, an electrical resistance coil mounted in the tube and spaced and insulated therefrom, pulverulent mica filling the space in the tube surrounding the coil, and a cable having wires entered through and secured to the apertured ears, and conducting wires projecting into the head for supplying current to the electrical resistance coils. 40
12. An electrical heater for oil wells, comprising, in combination, upper and lower heads, heating units arranged in tandem relation, each of said units comprising a tube, an electrical resistance coil mounted in and spaced and insulated from the tube, pulverulent insulation material filling the space between the coil and tube for conducting heat from the former to the latter, means connecting the adjacent ends of the tandem 45
- units, and a tube containing and closely fitting the units having its ends secured to the upper and lower heads respectively. 45
13. An electrical heater for oil wells, comprising a plurality of electrical heating units arranged in tandem relation, each comprising a tube, an electrical resistance coil mounted in and spaced and insulated from the tube, pulverulent insulation material filling the space between the coil and tube for conducting heat from the former to the latter, a tube having a length sufficient to receive the tubes of the units in tandem relation, and means to supply electric current to the coils. 50
14. An electrical heater for oil wells, comprising upper and lower heads, groups of heating units, each comprising a tube, an electrical resistance coil mounted in and spaced and insulated from the tube, binding posts projecting from the units into the upper head, binding posts projecting from the units into the lower head, bridge contacts connecting pairs of the lower binding posts, bridge contacts connecting the upper binding posts of the units which are not connected by the bridge contacts for the lower binding posts, and means to supply electrical current to the units through certain of the upper binding posts. 55

In testimony whereof, I have signed my name to this specification. 60

PERCIVAL F. BRINE.
